WALTER R. SCOTT, RALPH DUBINSKI, JR., AND PHELIX B. MAGIDSON, OF NOKOMIS,
ILLINOIS.

MINER'S CAP AND LAMP ATTACHMENT.

Application filed June 28, 1922. Serial No. 571,355.

To all whom it may concern:

Be it known that we, WALTER R. SCOTT, RALPH DUBINSKI, Jr., and PHELIX B. MAGIDSON, all citizens of the United States, 5 residing in the city of Nokomis, county of Montgomery, and State of Illinois, have invented a certain Improvement in a Miner's Cap and Lamp Attachment, of which the following is a specification.

10 Our invention relates to certain improvements on an attachment for a miner's cap and a clamp attachment for miner's lamp.

One object of our invention is to simplify the attachments by making them in one piece 15 instead of four or more pieces, as made in previous inventions.

Another object of our invention is to reduce the expense of the manufacture of same.

20 A further object of our invention is to hold the miner's lamp rigid so that the light from same will point or shine in the exact direction in which the miner is looking and also to prevent the occasional dropping of 25 lamp from miner's cap and to prevent the aggravating movement of lamp when the miner moves his head from side to side.

These objects are attained in the following manner, reference being made to the accompanying drawings, in which—

30 Figure 1 is a plan view of our improved miner's cap and lamp attachment.

Figure 2 is a side view; Figure 3 is a front view.

35 Referring to the drawings, 1 is a double

spring clamp which grips and holds the lamp in a rigid and upright position. 2 is a rib which is used in this instance to stiffen the section of attachment where the metal is weakest. 3 is a single spring clamp which holds the needle and wire container used for 40 cleaning the lamp burner. 4 is the section of the attachment which is riveted to the crown of miner's cap, and 5 is the section of the attachment which is riveted to the visor 45 of the miner's cap.

We claim:

In combination with a miner's cap and lamp, a lamp attachment made of a single piece of material and comprising an upright plate having means at its upper and lower ends to be fastened to the crown and visor of the cap respectively, a horizontal double spring clamp formed with the central portion of the upright plate and adapted to grip and hold the lamp in rigid position, and a spring clamp formed with the plate and adapted to hold a needle and wire container or the like for cleaning the lamp burner. 55

In testimony whereof, we have signed by name to this specification, in the presence of two subscribing witnesses.

WALTER R. SCOTT.
RALPH DUBINSKI, JR.
PHELIX B. MAGIDSON.
